(57) **CLAIM**

The ornamental design for a a power tool assembly, as shown and described.

DESCRIPTION

FIG. 1 is a perspective top front view of an upright-positioned embodiment of a power tool assembly showing my new design;

FIG. 2 is a front view thereof;

FIG. 3 is a rear view thereof;

FIG. 4 is a left side view thereof;

FIG. 5 is a right side view thereof;

FIG. 6 is perspective top rear view thereof;

FIG. 7 is a top view thereof;

FIG. 8 is a bottom view thereof;

FIG. 9 is a left side view of a side-positioned embodiment of a power tool assembly;

FIG. 10 is a right side view thereof; and,

FIG. 11 is a perspective top back view thereof.

The broken lines in the drawings depict environmental subject matter only and form no part of the claimed design.
